METAL WINDOW

Charles D. Pilant, Alhambra, Calif.

Application February 8, 1939, Serial No. 255,260

2 Claims. (Cl. 189—77)

My invention relates to a metal window of the particular type disclosed in U. S. Letters Patent No. 2,112,634 issued to me March 29, 1938.

The principal objects of my present invention are, to generally improve upon and simplify the construction of the metal window covered by my aforesaid patent, as well as other existing forms of metal windows having swinging sash, further, to provide in a metal window that includes a plurality of sash frames hinged so as to swing outwardly into inclined positions relative to the vertical plane occupied by the window frame and further, to construct the swinging sash so that panes of glass may be easily and quickly inserted and secured in the sash.

Further objects of my invention are, to construct the various parts of the window so as to provide maximum protection against entry by intruders, further, to construct the window frame and swinging sash so as to provide a highly efficient air, dust, and rain-proof window, and further, to provide a window that is entirely fire-proof.

A further object of my invention is, to provide relatively simple and easily operated means for simultaneously swinging the glazed sash into open or closed position.

With the foregoing and other objects in view, my invention consists in certain novel features of construction and arrangement of parts that will be hereinafter more fully described and claimed and illustrated in the accompanying drawings in which:

Fig. 1 is a front elevational view of a metal window constructed in accordance with my invention.

Fig. 2 is a horizontal section taken on the line 2—2 of Fig. 1.

Fig. 3 is a perspective view of the two members that combine to form the centrally arranged vertical member of the window frame.

Fig. 4 is a vertical section taken on the line 4—4 of Fig. 1.

Fig. 5 is an enlarged horizontal section taken on the line 5—5 of Fig. 4.

Fig. 6 is an enlarged horizontal section taken on the line 6—6 of Fig. 4.

Fig. 7 is a detail elevational view taken approximately on the line 7—7 of Fig. 4 with parts in vertical section.

Fig. 8 is an elevational view of one of the frames or sash that carry a panel or pane of glass.

Fig. 9 is an enlarged horizontal section taken on the line 9—9 of Fig. 8.

Fig. 10 is an enlarged horizontal section taken on the line 10—10 of Fig. 8.

Fig. 11 is an enlarged detail taken approximately on the line 11—11 of Fig. 1 with intermediate parts broken away.

Referring by numerals to the accompanying drawings which illustrate a preferred embodiment of my invention, 10 designates the horizontally disposed top member or rail of the window frame, 11 the vertically disposed side members or stiles and 12 the lower rail. These rails and stiles are preferably formed from heavy sheet metal and, extending upwardly from the outside edge of the top rail 10 is a flange 13.

15 The outer portions of the stiles 11 terminate in outwardly projecting flanges 14 that occupy the same vertical plane with the flange 13 and, formed between said flanges 14 and the main body portions of the stiles 11 are portions 15 that occupy inclined planes of approximately forty-five degrees relative to the planes occupied by the bodies of the stiles 11 and their flanges 14.

Depending from the outer edge of the lower rail 12 is a flange 16 that occupies the same vertical plane with flanges 13 and 14 and, secured by welding or otherwise to the lower portions of the flanges 14 of the stiles and positioned immediately above the outer portion of lower rail 12 and its flange 16 is a transverse rail having an intermediate portion 17 that occupies an inclined plane of approximately forty-five degrees and which corresponds with the inclined portions 15 of the stiles 11. The inner portion of this rail terminates in a vertically disposed flange 18 that occupies a position between the lower portions of the stiles 11, slightly inset from the corners between the inclined portions 15 and the main body portions of the stiles and, projecting forwardly from the lower portion of the inclined body 17 of this rail is a horizontally disposed flange 19 that projects a short distance forwardly from the vertical plane occupied by the front faces of the flanges 13, 14, and 16.

45 The ends of the upper and lower rails 10 and 12 are rigidly secured in any suitable manner, preferably by welding, to the ends of the stiles 11, thus providing a strong and substantial frame for the window.

In the construction herein illustrated, I have 50 shown a window having six sashes arranged in pairs, one above the other, but it will be understood that the window frame may be made larger or smaller so as to accommodate a number of sashes, greater or less than six.

55 Arranged midway between the stiles 11 is a

vertically disposed rail 20 of angle bar shape in cross section with flanges of equal width and the ends of this intermediate rail are rigidly fixed, preferably by welding, to the top and bottom rails 10 and 12 respectively. This intermediate rail is arranged so that its central line, or the apex between its flanges, occupies approximately the same vertical plane with the outer faces of the flanges 13, 14, and 16 and, thus the outer faces of the flanges of the central rail occupy inclined positions that correspond with the inclined positions of the portions 15 of the stiles.

Suitably secured, preferably by welding, to the under side of top rail 10 a short distance inwardly from flange 13 is the upper inner portion of a transversely disposed rail 21 that extends outwardly and downwardly and its lower outer edge terminates in a horizontally disposed flange 22, the latter occupying a position in front or outwardly from the flanges 13 and 14. This rail provides a point of attachment for the hinges that are carried by the upper sash and in addition said rail provides an effective dust and weather-proof closure between the upper ends of the upper sash and the top rail 10 when the sash are closed.

Spaced equi-distant apart from each other and from the top rail 10 and bottom rail 12 are transversely disposed rails 23, the ends of which are rigidly fixed, preferably by welding, to the stiles 11 and the intermediate portions of these transverse rails are connected, preferably by welding, to the intermediate member 29. Each of these rails 23 is provided on its upper inner edge with a vertically disposed flange 24 and on its lower outer end with a horizontally disposed flange 25, thus conforming in a general way to the cross sectional shape of the rails 21 and 17.

The inclined portions 15 of the stiles and the inclined flanges of the intermediate vertical rail 20 provide beveled seats for the correspondingly beveled upright side members of the window sash. The upper surfaces of the inclined portion 17 of the lower rail and the upper surfaces of the inclined portions 23 of the intermediate horizontally disposed rails provide beveled seats for the correspondingly beveled lower rails of the window sash, while the under surface of the inclined portion 21 of the upper rail and the under surfaces of the inclined portions 23 of the intermediate rail provide beveled seats for the correspondingly beveled upper rails of the window sash. Thus, the frame comprising upper and lower rails 10 and 11, together with upright rails or stiles 11 and the transverse rails 17, 21, and 23 constitute a strong and substantial, practically one piece, window frame having a plurality of sash openings of equal size for the accommodation of the hinged glazed sash.

Each sash comprises a rectangular frame that includes an upper rail 26, a bottom rail 27, and upright side rails 28, each frame being cast in a single piece. The upper rail 26 is provided with a beveled upper face 29 which, when the sash is closed makes direct contact with the under surface of the inclined member 21 of the top rail or the inclined portions 23 of the intermediate horizontal rails.

Formed integral with the ends of the top rails 26 are lugs 30 that form points of attachment for the inner plates of hinges 31, the outer plates thereof being suitably secured to the flange 22 of the upper rail 21 or to the flanges 25 of the intermediate horizontal rails. The side rails 28 of each sash frame are provided on their outer

edges with beveled faces 32 which, when the sash are closed fit snugly against the outer faces of the inclined portions 15 of the stiles 11.

The lower rails 27 are provided on their under sides with beveled faces 33 which, when the sash are closed fit snugly against the upper surfaces of the inclined portions 23 of the intermediate rails and upon the inclined central portion of the lower rail 17.

Thus, when the parts of the window are properly constructed and the sash are closed, weather-proof joints are formed between the sash and the window frame and immediately above each sash is a transverse rail, such as 21 or 23, that is inclined and which projects beyond the outer face of the window frame to provide an effective dust and rain shield.

Each upright side rail 28 of each sash is provided on its front inner edge with a pair of inwardly projecting flanges 34 which function as bearings for the side edges of the pane of glass that is positioned in the sash frame and, formed on the intermediate portion of each upright side member 28 adjacent the rear edges thereof are inwardly presented flanges 35 which also serve as bearings and retainers for the pane of glass positioned in the frame. The flanges 35 also function as points of connection for links forming a part of the sash raising and lowering means and which will be hereinafter more fully described.

Formed on the lower portions of the inner edges of the upright side members 28 of the sash frame and on the rear edges of the end portions of the bottom rail are flanges 36 which serve as bearings for the panes of glass positioned in the frames and, formed on the intermediate portion of the front edge of each bottom rail 27 is a flange 37 which also functions as a bearing for the panes of glass.

The flanges 34 and 35 on the upright side rails 28 and the flanges 36 and 37 on the bottom rails are spaced apart laterally of said rails a sufficient distance to accommodate a pane of glass such as G and which when inserted from the top of each frame fits snugly therein between the various flanges and with the upper edge of the pane of glass positioned directly behind the lugs 30 on the upper rail 29 of the sash.

Such construction enables the panes of glass to be easily and conveniently inserted in the sash, thus facilitating replacements in the event of breakage of the glass and, to secure the panes of glass in the sash putty as designated by P, or the like, is applied to the faces of the glass along the side and bottom edges thereof between the flanges 34, 35, 36, and 37 and if desired putty may be placed between the edges of the panes of glass and the metal rails of the sash against which said edges engage, such latter provision insuring air and weather-proof joints between the glass and metal.

In the event that it becomes necessary to replace broken panes of glass after the window has been assembled, the sash must be swung outwardly into position where the panes of glass while being inserted will clear the inner portions of the top rail 10 and the upper inner portions of the intermediate rails 23.

Arranged for vertical sliding movement upon the rear side of the flanged intermediate vertical rail 20 is a channel 38, the same being somewhat shorter than rail 10 and, formed in the central portion of the web of this channel adjacent its upper and lower ends are vertically disposed slots 39 for the accommodation of pins 40 that

project from the rail 20 and, the ends of these pins that pass through the web of the channel receive nuts 41, thus maintaining the channel for sliding movement on the rear side of the rail 20.

Pivots connected to the flanges of channel 38 are the upper ends of adjustable links 42 such as turn buckles, the lower ends thereof being pivotally connected to brackets 43 that are mounted on the flanges 35 that are formed on the upright side members 28 of the sash frames. These adjustable links or turn buckles 42 are arranged in pairs with one link connecting one of the side members 28 of each sash with the sliding channel 38.

The means utilized for imparting vertical sliding movement to channel 38 includes a housing 44 that is secured on top of the central portion of bottom rail 12 and, journaled for rotation in the removable inner wall 45 of said housing is the hub portion 46 of a pinion 47, the teeth of which mesh with the teeth of a pin tooth gear 48 that is mounted for rotation within the lower portion of housing 44 on top of bottom rail 12. This pin tooth gear has a hub 49 that has bearing in an opening formed in rail 12 and secured by a pin or otherwise to the pin tooth gear and its hub is the lower end of a vertically disposed threaded shaft 50. This shaft passes through a nut 51, the latter being held in the lower portion of a channel 38 by means of pins or screws 52 that pass through the flanges of said channel into the sides of the nut and, in order to maintain this nut in operative position lugs 53 project from the rear side of said nut and bear on the face of the web of the channel 38.

To maintain the pin tooth gear in operative position on the top of bottom rail 12, fingers 54 project from the lower portion of the cover plate 45 of the housing over the upper ends of the teeth of said gear and thence downwardly so as to bear on the flat upper face of the pin tooth gear between its teeth and the threaded shaft 50 (see Figs. 6 and 7).

Formed in hub 46 of pinion 47 is a non-circular recess 55 that functions as a socket for the reception of one end of a crank or other tool that is utilized in rotating the pinion.

To swing the glazed sash on their hinges, a tool such as a crank is utilized for imparting rotary motion to pinion 44, which pinion drives the pin tooth gear 48, thus imparting rotary motion to the threaded shaft 50 which moves nut 51 upwardly or downwardly as the case may be. When opening movement is applied to the sash, shaft 50 is rotated so as to cause nut 51 to move downwardly and as the nut is connected to channel 38 by means of the pins or bolts 52, said channel is moved downwardly on the flanged intermediate member 20.

Through the turn buckles 42 arranged between the sliding channel and the sash, the latter will be swung outward to the desired degree of angularity, thus giving ample ventilation through the window.

To close the sash, threaded shaft 50 is rotated so as to cause the nut to move upwardly on said shaft, thus correspondingly drawing the turn buckles upwardly and moving the sash into closed positions. When closed, the beveled upper faces on the top rails 26 of the sash fit snugly against the under sides of the beveled portions of the intermediate horizontal rails and the beveled

portion of the rail 21 that is positioned beneath top rail 10 of the window frame. When the sash are closed, the beveled lower faces 33 of the sash bear on top of the beveled portions of the intermediate rails 23 and on the beveled portion 17 of the rail that is positioned just above the bottom rail 12 of the window frame.

Likewise, the beveled faces 32 on the upright side members 28 of the sash bear snugly against the correspondingly beveled portions 15 of the stiles 11 and against the faces of the inclined flanges of intermediate vertical rail 20. Thus when the glazed sash are closed, weather-proof joints are provided between the rails of the sash and the various rails of the window frame. Should any play or lost motion develop in any of the hinged sash, this can be readily adjusted and taken up by proper manipulation of the turn buckles 42.

20 The transverse rails 21, 23, and 17, having their ends welded to the upright side members or stiles of the window frame, materially reinforce the latter and provide an extremely strong and substantial structure, in addition to providing an outwardly presented transversely disposed shield immediately above the upper ends of the hinged sash.

An especially desirable feature of my invention is, the construction of the sash frames which enables broken panes of glass to be readily removed and replaced by new panes, without the necessity for detaching the sash frames from the window frame.

Thus it will be seen that I have provided a metal window that is relatively simple in construction, inexpensive of manufacture and very effective in performing the functions for which it is intended.

It will be understood that minor changes in the size, form and construction of the various parts of my improved metal window, may be made and substituted for those herein shown and described, without departing from the spirit of my invention, the scope of which is set forth in the appended claims.

I claim as my invention:

1. In a metal window, a sash formed in a single piece and comprising top and bottom rails and vertically disposed side rails, a plurality of staggered flanges formed on the inner edges of the vertically disposed side rails and the bottom rail of said sash, a pane of glass positioned in said sash with its side and lower edges disposed between said flanges and which flanges are spaced apart longitudinally of the rails on which they are formed in order to form longitudinally disposed spaces for the reception of putty that secures the pane of glass to said sash.

2. In a metal window, a sash being formed in a single piece and comprising top and bottom rails and vertically disposed side rails, a plurality of staggered flanges formed on the inner edges of the vertically disposed side rails and the bottom rail of said sash, a pane of glass positioned in said sash with its side and lower edges disposed between said flanges, which flanges are spaced apart longitudinally of the rails on which they are formed in order to form longitudinally disposed spaces for the reception of putty that secures the pane of glass to said sash and the upper edge of said pane of glass being positioned behind the rear edge of the top rail of said sash.

CHARLES D. PILANT.
